UNITED STATES PATENT OFFICE

2,546,944

MOUNTING DEVICE FOR WINDOW
VENTILATING FANSMartin Hereward Fuller, Indianapolis, Ind., as-
signor to Climax Machinery Company, Indian-
apolis, Ind., a corporation of Indiana

Application February 12, 1948, Serial No. 7,775

2 Claims. (Cl. 98—94)

1

The present invention relates to a mounting device for window ventilating fans, and is primarily concerned with an improvement in the means for securing a ventilating fan unit in place in a window opening. The primary object of the invention is to provide a substitute for the integral ears heretofore provided in devices of the class under consideration, thereby facilitating the mounting of fans or the like in window openings, and overcoming what has come to be a serious difficulty in the art to which the invention pertains.

Further objects of the invention will appear as the description proceeds.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is an elevational view of a fan housing mounted in a window opening;

Fig. 2 is an enlarged fragmental perspective showing my novel mounting device in use;

Fig. 3 is a fragmental perspective showing a corner of a mounting frame and my bracket, which forms a part of the invention, before assembly; and

Fig. 4 is a broken perspective view similar to Fig. 2, but showing the opposite side of my mounting device.

Referring more particularly to the drawings, it will be seen that I have illustrated a portion of a standard window frame 6 having a sash 7 slidably mounted therein. I have illustrated also a ventilating fan unit including a frame 8 and a cage 9 received in the window frame between the sill 5 and the sash 7. The frame 8 comprises telescopically associated elements 10 and 11 which are laterally adjustable to fit the lateral elements of the window frame 6. The frame element 10 comprises a body sheet 10', a top flange 12, a bottom flange 13, and a side flange 14, said flanges being turned out of the plane of the body sheet so that they lie in planes perpendicular to the plane of the body sheet, the flanges 12 and 13 lying in parallel planes and the flange 14 lying in a plane substantially perpendicular to the planes of the flanges 12 and 13.

Similarly, the frame element 11 comprises a body sheet 18, a top flange 15, a bottom flange 16, and side flanges 17 and 17', similarly related to the body sheet 18 and to each other.

2

According to standard practice prior to my invention, the flanges 14 and 17 have been formed to provide integral ears projecting substantially above the planes of the flanges 12 and 15, respectively, said ears being perforated to receive fastening screws engageable in the lateral elements of the window frame 6. These projecting ears have posed a packing problem, in connection with shipment of units like the unit 8, to protect such ears against distortion and breakage; and additionally, it has been found that those ears are frequently bent or broken during handling in or delivery by retail stores, or in handling by the purchaser. Once such an ear has been bent, it has been found that the average householder is unable to return it accurately into the plane of the flange of which it is an extension; and, of course, once such an ear has been broken, it is substantially impossible to repair the unit without substituting a completely new mounting frame.

According to the present invention, I dispense with such ears. As is clearly to be seen in Figs. 2 and 3, the inner surface of the flange 17 lies substantially flush with the adjacent end 19 of the flange 15; and the upper end 20 of the flange 17 lies substantially in the plane of the upper surface of the flange 15. Near its end 19, the flange 15 is formed with an opening 21 which, in the preferred embodiment of the invention, is rectangular as shown. A bracket 22, comprising two arms 23 and 24 perpendicularly related to each other, is provided, intermediate the ends of its arm 23, with a tongue 25, preferably punched from the body of the arm 23. The free end 26 of the tongue 25 projects toward the plane of the bracket arm 24, and the tongue is displaced, from the plane of the arm 23, in a direction opposite to the direction of projection of the arm 24.

The distance of the root 27 of the tongue 25 from the plane of the arm 24 is so related to the distance of the adjacent end 28 of the opening 21 from the end 19 of the flange 15 that, when the tongue 26 is engaged in the opening 21 and the bracket 22 is shifted as far as possible toward the end 19 of the flange 15, the bracket arm 24 will be disposed substantially in the plane of the flange 17, while the arm 23 will be retained in planar engagement with the upper surface of the flange 15.

Obviously, the flange 12 of the frame element 10 will be formed with an opening similar to the opening 21 and similarly related to the flange 14, for the reception of the tongue of another bracket 22 oppositely arranged.

It will be clear that the unit 8 will be shipped with the brackets 22 disassembled from the flanges 12 and 15, so that there are no projecting elements analogous to the ears of standard practice, as above described. The brackets 22 will be assembled with the flanges 12 and 15 only after the unit 8 has been suitably positioned in the window frame 6. With the flanges 14 and 17 in contact with the adjacent elements of the window frame 6, and preferably with the sash 7 bearing upon the flanges 12 and 15, the brackets 22 will be assembled with said flanges by engaging their tongues 25 in the openings 21, whereby the bracket arms 24 will be brought into contact with the respective window frame elements. The arm 24 of each bracket is provided with a perforation 29 for the passage of a screw 30 which may be engaged in the window frame elements to secure the brackets, and consequently the frame elements 10 and 11, against displacement relative to the window frame.

Since the brackets 22 are not associated with the frame elements 10 and 11 during shipment of the unit 8, the packing problem above referred to does not arise; and similarly, there is no probability of damage to said brackets during handling in the retail stores. If, as is contemplated, the brackets 22 are associated with the unit 8 after said unit has been positioned in the window frame, and are disassembled from the unit before the unit is removed from the window frame, by the householder, there is substantially no possibility of damage to the brackets. Such damage may be further guarded against by making the brackets of material heavier or stiffer than that which is customarily used for the frame elements 10 and 11. But even if the brackets are damaged, there remains the substantial advantage that nothing except the damaged bracket need be replaced.

I claim as my invention:

1. A mounting device for a window ventilating fan comprising a sheet metal frame including two elements each comprising a body portion and flange portions turned out of the plane of the body portion and lying respectively in angularly-related planes, one flange portion of each element being provided, at a point near the plane of another flange portion of the same element, with an opening, and a bracket for each element, each

bracket comprising two arms having the same angular relation to each other as the said flange portions of such element, one arm of each bracket being provided with a tongue projecting out of the plane of such arm with its free end facing the plane of the other bracket arm, said tongue being receivable in said flange portion opening to locate said other bracket arm substantially in the plane of said other flange portion.

2. A mounting device for a window ventilating fan comprising two telescopically-associated frame elements, each such element comprising a body portion, a top flange portion and a side flange portion, said flange portions lying respectively in planes substantially perpendicular to each other and to the plane of said body portion and the end of each flange portion adjacent the other flange portion lying substantially in the plane of said other flange portion, said top flange portion of each element being provided, at a point near said side flange portion, with an opening therein, and a bracket for each element, each bracket comprising two perpendicularly-related arms, one bracket arm being provided with a tongue displaced from the plane of said arm in a direction opposite the direction of projection of the other bracket arm with its free end facing the plane of said other bracket arm, said tongue being receivable in the top flange opening of one of said elements with its free end projecting toward the side flange of the same element to locate said one bracket arm in planar contact with said top flange and said other bracket arm substantially in the plane of said side flange to project above said top flange.
